UNITED STATES PATENT OFFICE.

LESLIE V. GRANTIER, OF DETROIT, MICHIGAN, ASSIGNOR TO MCCORD RADIATOR & MFG. CO., OF DETROIT, MICHIGAN, A CORPORATION OF MAINE.

VAPOR-COOLING SYSTEM.

Application filed April 10, 1926. Serial No. 101,034.

This invention relates to a vapor cooling system for internal combustion engines such as are employed on motor vehicles.

In Patent No. 1,460,360, granted June 26, 1923, to Lester P. Barlow, a cooling system is shown employing a single circuit for the cooling medium. All of the latter must circulate through the radiator or cooler, thus delaying quick warming-up of the motor, which is particularly desired at any time and more especially in cold weather. Also in this Barlow system, steam or vapor is generated only under extreme conditions of load or service, with the result that the temperature of the cylinder walls is not maintained constant as desired.

The object of my invention is to provide a system having two interconnected circuits, one circuit to convey vapor from the cylinder jacket to the cooler and condensate from the latter, and the other circuit permitting a circulation of cooling liquid through the jacket without passing either through the cooler or the reservoir, thus allowing the motor to warm or heat up quickly irrespective of load, driving, weather or temperature conditions and remain at a substantially constant high temperature during operation.

Another object of my invention is to locate the supply tank or reservoir below the cylinder jacket and the cooler, so that the jacket and cooler may drain through the respective circuits into the reservoir when the system is idle and thus prevent any possibility of freezing-up of either the jacket or the cooler.

A further object of my invention is to make the reservoir of such capacity that it will accommodate sufficient cooling liquid to take care of the needs of the circuits under all conditions of operation and constitute a reserve supply to compensate for loss of liquid by leakage or evaporation.

A further object of my invention is to have the two circuits connected in advance of the pump and leading to a single inlet thereof, so as to assure a constant flow of cooling liquid to the pump and not create air pockets in the pump, and automatically

control the flow through the two circuits without check valves or thermostats or other means.

A further object of my invention is to make the inlet conduit of the second circuit larger in diameter than the outlet conduit, so as to offer a low resistance to the flow of cooling liquid through the inlet conduit and thus avoid any appreciable rise of the level in the jacket during the operation of the system.

The invention consists further in the matters hereinafter described and claimed.

In the accompanying drawing, the single figure thereof, represents in a more or less diagrammatic manner, a cooling system employing the features of my invention and shown applied as to an internal combustion engine as employed on motor vehicles.

In the drawing, 1 indicates the cylinder jacket of the engine; 2 indicates a space above the water jacket, permitting steam or vapor to rise from the water or other cooling liquid in the jacket when the temperature of the engine has risen high enough to vaporize the liquid in the jacket; 3 indicates a cooler as in the form of a radiator located in front of the engine and connected with the space 2 by a conduit 4; 5 indicates a supply reservoir or tank located below the jacket 1 and the cooler 3, and connected with the lower end of the latter through a connection 6.

7 indicates a pump of any preferred type and which has a single inlet and an outlet. Conduits 8 and 9 are connected with the inlet and outlets, respectively, of the pump. These conduits extend upwardly from the pump and are connected with the water jacket 1, preferably at different levels, as shown. The conduit 9 opens into lower portion of the jacket, while conduit 8 opens into the upper portion jacket at approximately the normal height of the liquid level in the jacket 1, as indicated by the dotted line a.

The reservoir 5 is connected with the inlet of the pump by a connection 10, this connection joining the connection of the conduit 8 with the pump, so that the flow of liquid through the conduit 8 into the pump will aid

or have an ejector effect on the liquid in the connection 10 due to the velocity of the flow into the pump.

The reservoir or tank 5 has a filler opening

- 5 11 normally closed by a cap. The tank and the lower end of the cooler 3 are vented to the atmosphere through a vent 12 between the lower end of the cooler and the upper portion of the tank, so as to maintain atmospheric pressure in the lower end of the cooler or condenser, and the space above the liquid or water in reservoir.

The system shown and described operates as follows:

- 15 The tank or reservoir 5 is filled with liquid to an extent sufficient to supply the needs of the system, and also serve as a suitable reserve. In practice, with an assembly as shown in the drawing, the tank 20 or reservoir would be completely filled to a level indicated by the dotted line *b*, the jacket at this time being free of liquid. The pump 7 being at the lower level of the tank 5 will be flooded and the liquid will stand in 25 the conduits 8, and 9 to the level *b*.

On starting the motor or engine, the pump 30 7 will fill the jacket 1 through the conduit 9, drawing water for the purpose from supply reservoir 5, the level in the latter lowering to approximately that indicated by the dotted line *c*. When the jacket fills to the level *a*, the liquid in the tank is at that time no further lowered and remains approximately constant at level *c* until steam or 35 vapor is generated in the jacket 1 by the heat of the engine. A continuous circulation of water or liquid to the jacket through conduit 9 causes liquid in the jacket to flow into the upper end of the larger conduit 8, and 40 fall therethrough to the column of water or liquid already therein. This conduit 8, is made sufficiently large in diameter so as to offer a low resistance to the passage of water or liquid therethrough and thus avoid any appreciable rise of the level *a* in the jacket.

This circulation continues without passing through either the cooler 3 or the reservoir 5, with the result that circulated liquid is not subjected to any appreciable cooling 50 action, and its temperature quickly and rapidly rises to the boiling point. This allows the motor to warm up quickly and remain at a constant temperature during operation, irrespective of load, speed, or weather 55 conditions. As soon as steam or vapor is given off at the liquid level *a* in the jacket 1, it rises into the top space 2 and passes therefrom into the upper end of the cooler 3 where such vapor is condensed as it passes 60 downward through the passages of the cooler. A fan 13 is associated with the cooler, and is preferably operated by the engine, so as to draw currents of air through the cooler to condense the vapor entering 65 into the same.

The condensed vapors flow into chamber or head 14 at the lower end of the cooler, as shown in the drawing. From thence the condensate flows into the tank or reservoir 5 through the connection 6, so as to return to 70 the system and thus allow the cooling liquid to be used over and over again without replenishing except at long intervals.

When the cooling liquid vaporizes at the top of jacket and fills the space 2 and the upper part of the cooler 3, the level of the liquid in the tank 5 lowers slightly below that indicated by *c*, due to the fact that sufficient liquid must be drawn from the reservoir to make up for the initial filling with vapor of that portion of the system designed to receive the same.

There is sufficient amount of liquid contained at all times in the reservoir 5 below the level *c* to supply for a considerable 85 period of time the make up water necessary to replenish or compensate for leakage or losses in the system and also to operate as a liquid head for the pump. This avoids the use of check valves, thermostats, or other controls as the pump is at all times operatively submerged. The conduits 8 and 9 are connected in advance of the pump 7 and this connection is disposed below the level *c* so as to be submerged at all times with liquid. 95 The pump has a single inlet 7^a so that a single pump may be used with the two conduits.

By having the vent 12 located between the lower end of the cooler 3, and the maximum 100 level *b* of the liquid in the tank 5 as indicated in the drawing, any air in the cooler will be displaced by the lighter steam entering the top of the same.

The system shown and described embodies 105 two circuits. One circuit includes the vapor or steam space 2, the cooler or condenser 3 and the tank or reservoir 5. The other circuit includes the jacket 1, pump 7 and conduits 8 and 9. Both circuits join at the inlet 7^a of pump 7 and combine through conduit 9 to jacket 1, where they separate through chamber 2 and conduit 8. The second circuit forms a by-pass for the first, and thus allows for a quick heating-up of the 115 engine on starting and assures a constant temperature therefor during operation.

The reservoir 5 has a capacity sufficient to hold all of the liquid required by the system and also a little more for reserve supply. 120 The reservoir 5 is located below the jacket 1 and the cooler 3 and by its connection with both allows the liquid in the cooler and the jacket to drain into the reservoir when the system is idle. The mechanism of the pump is such that it permits the liquid to slowly drain therethrough, and thereby allow the engine cylinders to retain heat longer than should the pump allow for a rapid drain. The liquid at all times stands in the 130

5 conduit 8 above the inlet 7^a and its connection with the reservoir 5, thereby preventing any steam or vapor entering the vapor circuit except through the upper end of the cooler or condenser 3.

10 The details shown described may be variously changed and modified without departing from the spirit and scope of my invention. Moreover, in referring to the Barlow system, I wish it to be understood that my invention is not limited or restricted in its use to that system, the latter being mentioned for illustrative purposes.

I claim as my invention:

15 1. In a vapor cooling system for internal combustion engines, the combination with a cylinder jacket and a cooler, of two circuits, one to convey vapor from the jacket to the cooler and condensate from the latter, 20 and the other permitting the circulation of cooling liquid through the jacket without passing through the cooler, a reservoir below the jacket and connected with both circuits in a manner permitting both the jacket and the 25 cooler to empty into the reservoir when the system is idle, said reservoir being of a size to hold more liquids than actually required by the system so as to maintain a reserve supply therefor, and a circulating pump in 30 the system.

2. In a vapor cooling system for internal combustion engines, the combination with a cylinder jacket and a cooler, of two circuits, one to convey vapor from the jacket to the cooler and condensate from the latter, and the other permitting the circulation of cooling liquid through the jacket without passing through the cooler, a reservoir located below the jacket and connected with both 40 circuits in a manner permitting the jacket and cooler to empty into the reservoir when the system is idle, said reservoir being of a size to hold more liquids than actually required by the system so as to maintain a 45 reserve supply therefor, and a circulating pump in the system and having a single inlet to receive liquids from both circuits.

3. In a vapor cooling system for internal combustion engines, the combination with a cylinder jacket and a cooler, of a circulating pump in the system, a reservoir below the cooler and connected therewith, said reservoir being of a size to hold more liquids than actually required by the system so as to maintain a reserve supply therefor, and two circuits, the first for conveying vapor from the jacket to the cooler and condensate from the latter to the reservoir, and the second circuit permitting the circulation of cooling liquid through the jacket without passing through the cooler, said reservoir being connected with the pump in a manner to supply sufficient liquid to the second circuit without lowering the liquid level in the

reservoir below the operative level of the 65 pump.

4. In a vapor cooling system for internal combustion engines, the combination with a cylinder jacket and a cooler, of a reservoir below the cooler and connected therewith, 70 two circuits, the first to convey vapor from the jacket to the cooler and condensate from the latter, and the second circuit permitting circulation of cooling liquid through the jacket without passing through either the 75 reservoir or the cooler, said reservoir connected with both circuits in a manner permitting the jacket and cooler to empty into the reservoir when the system is idle, said reservoir being of a size to hold more liquids 80 than actually required by the system so as to maintain a reserve supply therefor, a circulating pump in the system, and a vent in the first circuit between the maximum liquid level of the reservoir and the lower end of the cooler and arranged to vent both the cooler and the reservoir.

5. In a vapor cooling system for internal combustion engines, the combination with a cylinder jacket and a cooler connected therewith, of a circulating pump below the jacket and the cooler, a reservoir below said cooler and connected with the cooler and pump, respectively and located between the same, 90 said reservoir being of a size to hold more liquids than actually required by the system so as to maintain a reserve supply therefor, inlet and outlet conduits for the pump and opening into the jacket, the inlet conduit extending upwardly and being larger than the outlet conduit so as to offer a low resistance to the flow of cooling liquid through the portion of the conduit between the jacket and the water level in the conduit above the pump.

6. In an internal combustion engine vapor cooling system open continuously to the atmosphere and operating at all times at atmospheric pressure, the combination with a cylinder jacket having a steam space above the same and a cooler having its upper end connected with said space, of a circulating pump located below the cooler and the jacket, supply and overflow conduits extending upward from the pump and providing a direct connection for its discharge and intake sides, respectively, with the jacket so that the cooling liquids may be circulated by the pump without passing through the cooler, said conduits opening into the jacket at different levels with the overflow conduit at the normal liquid level to be maintained in the jacket and the supply conduit below the same, and means connecting the lower end of the cooler with the intake of the pump so that the cooler may drain to the pump.

7. In a cooling system for internal com-

bustion engines, the combination with a cylinder jacket and a cooler, of a supply reservoir located below the jacket, two circuits, one for conveying vapor from the jacket to the cooler and condensate therefrom, and the other permitting the circulation of cooling liquid through the jacket without passing through either the cooler or the reservoir, a manifold providing a connection between

the circuits below the jacket, said reservoir 10 being connected to the circuits through the manifold, and a circulating pump in the system.

In testimony that I claim the foregoing as my invention, I affix my signature, this 2d 15 day of April, 1926.

L. V. GRANTIER.
